UNITED STATES PATENT OFFICE.

BALTAZAR WILHELMUS TIENHOVEN, OF THE HAGUE, NETHERLANDS, AS
SIGNOR TO COENRAAD BAKKER, NICOLAAS JOHANNES BOON, EMILE
LOUIS CONSTANT SCHIFF, AND JOHAN CORNELIS GONDRIAAN, OF SAME
PLACE, AND ARNOLD VAN WYCK, OF RENKUM, NETHERLANDS.

ROTARY MOTOR.

SPECIFICATION forming part of Letters Patent No. 633,669, dated September 26, 1899.

Application filed May 15, 1899. Serial No. 716,927. (No model.)

To all whom it may concern:

Be it known that I, BALTAZAR WILHELMUS TIENHOVEN, a subject of the Queen of the Netherlands, and a resident of The Hague, 5 Netherlands, have invented a certain new and useful Improvement in Rotary Motors, of which the following is a specification.

The invention relates to rotary steam-motors, and has for its object to secure the easy 10 and regular working of the same when running at a great speed up to fifteen hundred revolutions per minute.

The improved motor requires an exceedingly small expenditure of steam, is of simple 15 construction, and very cheaply built.

The invention is illustrated in the accompanying drawings, in which—

Figure 1 is an end elevation of the engine. Fig. 2 is a side elevation of the same. Fig. 3 20 is a plan view. Fig. 4 is a vertical sectional view, and Fig. 5 is a detail view.

The new motor comprises a cylinder furnished with removable covers *a* and *b* and with a division plate or disk *e*, dividing its 25 interior into two parts *c* and *d*, a shaft *i*, mounted to rotate in the cylinder, and a bucket or vane wheel mounted on the shaft *i*. Steam is admitted through a pipe *f* into one of the chambers or divisions *c* of the cylinder, 30 from whence it passes through slits *g*' and *g*'', formed at an angle of about forty-five degrees in the division-plate *e* into the other chamber *d*, in which the bucket or vane wheel is mounted, and being directed to impinge against the buckets or vanes causes 35 the wheel to rotate.

The steam-inlet openings *g*' and *g*'' are regulated by slide-valves *k*, operated through screw-and-lever mechanism *l* from a hand-wheel outside the cylinder. The steam passes 40 out through pipe *m* at the lower part of the cylinder.

A fly-wheel and a belt driving-pulley may be attached to the motor-shaft *i*, or the shaft may be coupled direct with the apparatus to 45 be driven.

Having now described my invention, what I claim as new, and desire to secure by Letters Patent, is—

In combination in a rotary steam-motor, 50 the casing, the shaft, a partition arranged within the same, dividing the interior into a small and a large compartment, a stem-inlet into the smaller compartment, an exhaust leading from the larger compartment, a vane-wheel arranged in the large compartment, 55 oblique slits extending through said partitions on each side of said shaft, a vertical valve-stem extending out of the top of said casing, a valve-wheel carried thereby a sliding valve controlling each slit, and independent operating connections between each valve and said common valve-stem, substantially as described.

In witness whereof I have hereunto set my 65 hand in presence of two witnesses.

BALTAZAR WILHELMUS TIENHOVEN.
